Fraser, Turk & Myers.

UNITED STATES PATENT OFFICE.

EDWARD E. GOLD, OF NEW YORK, N. Y., ASSIGNOR TO GOLD CAR HEATING & LIGHTING COMPANY, OF NEW YORK, N. Y., A CORPORATION OF NEW YORK.

PROTECTED THERMOSTAT.

1,418,913.

Specification of Letters Patent. Patented June 6, 1922.

Application filed March 10, 1921. Serial No. 451,191.

To all whom it may concern:

Be it known that I, EDWARD E. GOLD, a citizen of the United States of America, residing in the borough of Manhattan, city, 5 county, and State of New York, have invented certain new and useful Improvements in Protected Thermostats, of which the following is a specification.

This invention relates to thermostatic devices such as are commonly used to control apparatus adapted to heat a room, auditorium or other chamber, and is particularly adapted for use to control the heating of a railway car.

15 It is of importance that the electrically operated parts of a device of the above described character shall be concealed and rendered inaccessible so as to avoid the possibility of being tampered with by curious 20 or meddlesome persons, and, therefore, rendered inoperative.

It is, however, equally important that the thermo-motive element, by which the electric switch mechanism is controlled, should 25 be exposed so as to permit free circulation about the same of the air in the chamber, the temperature of which is to be regulated thereby.

The above-mentioned ends have been attained by the invention herein disclosed, in which the electric switching elements are mounted upon the rear face of a shield or protecting plate and the thermo-motive element is mounted upon the face of the same 35 plate. The shield, as herein disclosed, is used as a cover for an outlet box adapted to receive and house the switching mechanism mounted on the back of the shield.

The thermo-motive element, may, if desired, be enclosed by a perforated dome or cover which serves as a protector, but at the same time will permit free circulation of air about the thermo-motive element.

Other novel features of the invention include an operating lever mounted on the face of the shield and having an operative connection with the switching mechanism, and novel means for adjusting the thermo-motive element to render the same effective 50 at different temperatures.

In the accompanying drawings illustrating one form of the invention,

Figure 1 is a central vertical cross section on the line 1—1 of Fig. 2.

Fig. 2 is a face view of the lower part 55 of Fig. 1, parts being broken away to expose underlying mechanism.

Fig. 3 is a fragmentary view of the switching mechanism shown in Fig. 1, with the switch moved to a different position. 60

Certain parts of the invention herein disclosed, such, for example, as the details of the switching mechanism and the thermo-motive element by which the same is controlled, are illustrated and described in the 65 prior patent to Kitchen, No. 1,214,323, of January 30, 1917, and are not claimed per se in this application.

Referring more particularly to Fig. 1, the present invention comprises a shield or 70 face plate 20 to the rear of which is secured, by brackets or other suitable devices 21, a support 22 of insulating material upon which the electric switching mechanism is mounted. This electric switching mechanism, which is substantially the same as that of the above-mentioned Kitchen device, comprises a switch arm 23 adapted to swing about a bearing member 24 (Fig. 3), 75 mounted in a switch support 25 secured to the support 22. A spring 26, connected at one end to the switch support and at the other end to an arm of the switch lever, normally tends to hold the switch lever in 80 contact with one or the other of two electric terminals 27, 28, and, when moved slightly more than half-way in each direction, causes the movement of the switch arm to be suddenly completed, so as to be connected with the alternative electric terminal. A second spring 29 normally tends 85 to move a lever 30 toward the left, as viewed in Fig. 1, and thereby maintain the switch lever in contact with the electric terminal 28. 90

The above-described switching mechanism differs from that disclosed in the aforesaid Kitchen patent, in that the lever 30 is extended beyond the bearing element 24, and has its end bent back to form a toe 31 embraced between two short arms 32 extending from the rear of the switch lever so as to form a pin-and-slot connection by which the switch is thrown to its Fig. 1 position by the spring 29. 95

Other details of the switching mechanism, as well as the electric connections, constitute no part of the present invention and may,

for example, be similar to corresponding parts of the Kitchen patent heretofore referred to.

According to the present invention, the movements of the switching mechanism are controlled by an operating lever 33 pivotally connected at 34 to a support 35 secured by any appropriate means to the face of the shield plate 20 as by having its ends passed through perforations in said plate and firmly riveted thereto.

Mounted between a bearing element 36 adjustably secured to the face plate 20 and an adjusting screw 37 in the lever 33, is a thermo-motive element 38 of the same general character as that disclosed in the above-mentioned patent to Kitchen. This thermo-motive element, as herein disclosed, comprises two hollow disk-like receptacles which may contain a small amount of any suitable volatile fluid, such, for example, as ethyl-chloride, adapted to cause the disks to expand as the temperature increases, and to contract when the temperature is again reduced.

As a means for adjusting the thermo-motive element so as to cause the same to be effective at any desired temperature, the bearing element 36 is in the form of a screw 30 in threaded engagement with a nut 39 mounted for rotation in the plate 20. Endwise movement of the nut 39 is prevented by means of a strap 40 (Figs. 1 and 2), secured near its ends to the face of the plate 20 by screws or other suitable fastening devices 41, and having its central portion bridged over and in contact with the face of said nut.

The end of the bearing element 36 may be 40 non-circular in its form and be embraced by an opening of corresponding form in the strap 40, so that the bearing element will have a slideable but non-rotative connection with said strap.

45 An adjusting arm 43 fixed to the nut 39, serves as a means for rotating the same, the outer end of said arm serving as an index to cooperate with an indicator plate 44 bearing indicia of different temperatures. If 50 desired, the adjusting arm 43 may be provided with a knob 45 or other suitable means for moving the same.

The operating connection between the levers 33 and 30, as herein disclosed, comprises 55 a link 46 having its ends passed through openings in the respective levers, and terminating in enlargements 47, 48, so as to form a tie bar. If desired, the end of the link 46, which is secured to the lever 30, may 60 be separated therefrom by a bushing of insulating material 49. A perforation 50 in the face plate 20 permits free endwise movement of the link 46.

As a means for holding the thermo-motive 65 element confined between the bearing 36 and

the lever 33, attaching studs 51, 52 may be soldered or otherwise secured to its opposite faces. The stud 51 may, if desired, be threaded in a socket in the end of the bearing member 36, and the end of the stud 52 70 may be provided with a spherical end surface 53 to engage a recess of like form in the inner end of the adjusting screw 37.

The thermo-motive element 38 and operating lever 33 may be protected by a perforated dome or cover 54, which may be secured in place by screws or other suitable fastening means 55 passing through said dome and having threaded engagement with the up-turned ends of the strap 40. A cut-away portion 56, in the lower portion of the base of the dome, provides for the movement of the adjusting arm 43.

Preferably, the face plate 20 will be used as a cover plate for a junction box which 85 may be secured by means of suitable fastening devices as 58, 59, in the wall of the chamber of which the temperature is to be regulated. The face plate may be secured to such junction box by means of screws or 90 other suitable fastening devices 60.

The operation of the device is as follows:-

If it be desired to maintain the temperature of the controlled chamber at 70 degrees, 95 the adjusting lever 43 will be moved to the designation 70 on the indicator plate 44. The adjustment of the parts of the mechanism and the amount of volatile fluid in the thermo-motive element 38 will be such, that if the temperature of the room is less than 70 degrees the disks 38 will be collapsed and the spring 29 will hold the arm 30 and connected switch lever 23 in the positions indicated in Fig. 1.

As the temperature increases, the thermo-motive element will expand so as to cause the operating lever to be rotated in a clockwise direction about the pivoted connection 34, and by means of the link 46, cause the lever 30 to throw the switch lever 23. The slip connections at the end of the link 46 will permit the spring 26 to complete the movement of the switch lever when once initiated, so as to effect a rapid break and make 110 at the switch terminals. The adjustment of the parts and amount of volatile fluid in the thermo-motive element should be such that the switch mechanism will be thrown when the temperature of the room is equal to or 120 slightly above 70 degrees. As the temperature falls to or slightly below 70 degrees, the thermo-motive element will collapse, thus permitting the spring 29 to restore the switch mechanism to the position indicated 125 in Fig. 1.

If it is desired that the room be maintained at a temperature greater than 70, the controller handle is thrown to the right (Fig. 2), as a result of which the bearing 130

element 36 is slightly withdrawn so as to separate the points between which the thermo-motive element is confined. As so adjusted, it will require a greater temperature 5 to expand the thermo-motive element to such extent as to throw the switch and thereby cut out the heating apparatus.

Vice versa, if it is desired that the room be maintained at a temperature below 70, the 10 adjusting arm 43 is moved to the left with results just the opposite of those last described.

With the device constructed as above described, it will be observed that all of the 15 electric mechanism is enclosed and protected within the junction box. The thermo-motive element, however, is well exposed so that the air of the room may freely circulate about the same. The shield or cover plate 20, which separates the thermo-motive element from the electric switching mechanism, prevents the device from being tampered with by curious or meddlesome persons, since the imperforate plate renders it impossible to insert a wire, hair pin, hat pin, or the like into the electrically-operated parts of the mechanism with the usual disastrous results.

The invention, however, provides the same 30 refinements of adjustment and cooperative relation between the thermo-motive element and the parts operated thereby, as though all parts of the device were upon the same face of the shield or guard plate.

35 Although the invention is herein illustrated as applied in its preferred form, it is understood that modifications and changes may be made within the scope of the appended claims.

40 What I claim is:

1. A thermostat comprising an electric outlet box, a cover plate therefor, an electric switching device mounted on the inner face of said plate and housed by said box, a thermo-motive controlling element for said device mounted on the outer face of said plate, 45 said plate serving as a shield to prevent access to the electric parts of said thermostat housed in said box.

50 2. An adjustable thermostat comprising a

support, an electric switching device and its connected operating lever mounted on opposite sides of said support, an adjustable bearing also mounted on said support, a thermo-motive element confined between said bearing 55 and said operating lever, and means for varying the position of said adjustable bearing and thereby effecting an adjustment determinative of the temperature at which said switching device will be operated by said 60 thermo-motive element.

3. An adjustable thermostat as specified in claim 2, in which the adjustable bearing comprises a screw connected with the thermo-motive element, a nut for said screw rotatably mounted in the support, a retaining member bridging the face of said nut to prevent endwise movement relative to said support, said screw having a sliding but non-rotative connection with said retaining member, and indexing means comprising an arm connected with said nut and by which it may be rotated to effect an adjustment.

4. A thermostat comprising a plate, an electric switching device mounted at the rear 75 of said plate, a switch operating lever mounted on the face of said plate, a thermo-motive controlling element for said device mounted on the face of said plate in operative relation with said switch operating lever, and a link movable endwise through an opening in said plate, said link connecting the switching device with said operating lever, said plate forming a shield to prevent access to the electric parts of said thermostat 85 from the front.

5. A thermostat as specified in claim 4, in which the link comprises a draw bar for transmitting movements of said lever in one direction to said switching device, a slip connection being provided between said link 90 and the interconnected parts to permit the switch to complete an initiated movement independently of the movement of said lever, and thereby effect a quick break and make 95 with the switch terminals.

In witness whereof, I have hereunto signed my name.

EDWARD E. GOLD.
